UNITED STATES PATENT OFFICE.

EDWARD G. LADEWICH, OF MANSFIELD, OHIO, ASSIGNOR TO MCBEE-LADEWICH COMPANY, OF MANSFIELD, OHIO, A PARTNERSHIP.

DESIGN FOR A MONUMENT.

Application filed April 9, 1925. Serial No. 12,076. Term of patent 7 years.

To all whom it may concern:

Be it known that I, EDWARD G. LADEWICH, a citizen of the United States, residing at Mansfield, in the county of Richland and State of Ohio, have invented a new, original, and ornamental Design for a Monument, of which the following is a specification, reference being had to the accompanying drawing, forming part thereof.

The figure is a perspective view of a monument showing my new design.

The entire monument shown in the drawing is a complete and unitary design for memorial monuments and includes the monument proper as well as the flower receptacle at the front thereof.

I claim:

The ornamental design for a monument as shown.

E. G. LADEWICH.
